ATTORNEY

UNITED STATES PATENT OFFICE

CECIL H. RINEHART, OF BRISTOW, OKLAHOMA

HOSE SUPPORT AND ELEVATOR

Application filed June 12, 1930. Serial No. 460,698.

My invention relates to water fountains and more particularly to a device of that character for servicing automobiles and like vehicles at filling stations and constitutes 5 improvements over my co-pending application Serial Number 451,237, the principal object of my invention being to provide means for elevating a servicing fountain from a level below the line of frost to a 10 convenient position for operating the device.

It is a further object of this invention to embody simple and effective means for sustaining the fountain at different elevations and to cushion the return of the device to 15 lowered position.

In accomplishing these and other objects of my invention I have provided improved details of structure the preferred form of which is illustrated in the accompanying 20 drawings, wherein:

Fig. 1 is a central vertical section of a servicing fountain embodying my invention, illustrating the elevating mechanism, parts being broken away to more clearly show the 25 construction of the device.

Fig. 2 is a fragmentary, perspective view of a hose support and locking member, and of a guide associated therewith.

Fig. 3 is a cross section of the container 30 and servicing mechanism on the line 3—3 Fig. 1.

Referring more in detail to the drawings:

1 designates a container, preferably constructed of metal and inserted in an opening 2 at some convenient location on the filling station premises, the upper end of the container extending through a concrete floor 3.

Extended through an opening 4 in the 40 container wall and leading from a source of water supply is an inlet line 5 provided on the end projecting into the container with a valve 6 for controlling flow of liquid into a flexible conduit 7, secured to the valve by 45 a clamp 8.

In order that the outer end of the hose, provided with the usual bib 9 for filling radiators and the like, may be readily moved from a position below freezing depth to a 50 more accessible location, adjacent the ground

surface, I have provided a supporting and elevating mechanism generally designated 10.

The elevating apparatus includes a pair of parallel shafts 11 and 12, connected at their upper ends, and spaced sufficiently to be mounted astride the wall of the container, the shaft 11 slidably engaging a longitudinal, tubular guide 13 having outwardly directed flanges 14 fixed to the outer wall of the container by welding or the like as indicated at 15.

Integral with the inner shaft, relatively near the lower end thereof and projecting inwardly from the shaft is an apertured arm 16. A supporting bracket 17 in the form of a band is secured to the arm by a bolt 18 and surrounds the cylindrical barrel 19 of a jack 20.

Externally threaded lower and upper ends 21 and 22 of the cylindrical barrel are adapted to respectively receive a foot member 23 and a cap screw 24, a fitting 25 being threaded into a port 26 of the foot member to communicate the cylinder with a hose 27 leading from the jack through the open end 75 of the container so that the jack may, thereby, be connected to a source of compressed air or the like for elevating a piston 28 reciprocally mounted in the barrel.

The piston 28 preferably includes a pair 80 of spaced cups 29 and 30 secured to the lower end of an elevating rod 31 by nuts 32. A concentric opening 33 in the cap screw 24 is adapted to slidably receive the rod 31 which terminates at its upper end in a reduced shank 85 34, adapted to be received in an opening 35 adjacent the end of a supporting arm 36 maintained in fixed position on the end of the rod by a washer 37 and by a nut 38 applied to the threaded end 39 of the shank 34. Cushioning springs 40 and 41 are respectively provided in the bottom of the cylinder and on the rod 31 above the piston.

A relief port 42 in the cap screw 24 permits 95 discharge of air compressed in the cylinder above the pump plunger on its upward stroke, and a series of ports 43 near the top of the cylinder relieves the pressure in the cylinder when the pump plunger has reached its upper limit of travel so that only sufficient resistance 100

will be offered the piston on its return or downward stroke to effect a smooth and slow return of the supporting arm.

The supporting arm includes an integral 5 ring portion 44, substantially concentric in relation with the cylinder for receiving the conduit 7; a spherical member 45 secured on the hose adjacent the bib being adapted to rest on the arm when the hose is returned to 10 retracted position in the container by a weight 46 suspended on the hose by a pulley 47.

Threaded on the outer end of the supporting arm is a head 48 having an enlarged socket 49 for receiving a bearing ball 50 yielding- 15 ly urged outwardly against the indent edge 51 of the socket by an expansion spring 52 seated in the supporting arm adjacent the enlarged socket 49.

A channel member 53 preferably U-shaped 20 in cross section having outwardly directed flanges 54, is fixed to the inner face of the container wall by welding or the like to serve as a guide for the head 48 in its reciprocating travel in the container, and sockets 55 25 may be provided in the base of the channel for seating the ball 50 urged into said socket under tension of the spring 52 so that the supporting arm and the discharge end of the hose will be sustained in elevated relation 30 in the container.

To facilitate manual elevation of the supporting arm when air pressure for the jack is not available I have pivotally attached a handle 56 to the upper end of the shaft 12 35 by a bolt 57, the handle normally remaining in lowered position adjacent the shaft.

With an apparatus constructed and assembled as described and with the supporting arm in lowered position in the container, compressed 40 air may be admitted to the jack through the port 26 to force the piston upwardly, thereby elevating the supporting arm and the discharge end of the hose to an accessible position near the surface of the ground.

Upon reaching its upper limit of travel the bearing ball in the head of the supporting arm engages the upper socket in the guide channel, thus preventing return of the supporting arm into the container until a sufficient 45 amount of pressure is applied on the arm to disengage the ball from the socket against the tension of the spring.

During the warm seasons of the year the discharge bib may be maintained in entirely 55 elevated position, however, when there is danger of light frost the lower socket 55 maintains the supporting arm sufficiently far below the surface of the ground to admit the bib into the container so that the container 60 may be covered. While this position of the support is not as accessible as the entirely elevated position, it eliminates the necessity of elevating the support each time a car is to be serviced.

65. As soon as the danger of heavy frost ap-

proaches the supporting arm is moved to its lower limit of travel when not in use to prevent freezing of the water in the conduit 7.

If, for any reason, it is desirable to manually elevate the bib the operator pulls upwardly on the handle 54 until the bearing ball is seated in the upper socket.

With the structure heretofore described the bib may be readily elevated either manually or automatically and while other means such as a long conical spring may be substituted for elevating the bib, the present mechanism has proven most satisfactory.

What I claim and desire to secure by Letters Patent is:

1. In apparatus of the character described, a container, an inlet pipe extending into the container, a movable support in the container, a flexible conduit having one end connected to the inlet pipe and the opposite end normally sustained by the support, and pressure-actuated means for elevating the support in the container.

2. In apparatus of the character described, a container, an inlet pipe extending into the container, a movable support in the container, a flexible conduit having one end connected to the inlet pipe and the opposite end normally sustained by the support, means for elevating the support in the container including a barrel, a piston in the barrel, means for connecting the piston to the support, and means for admitting fluid pressure to the barrel to elevate the piston.

3. In apparatus of the character described, a container, an inlet pipe extending into the container, a movable support in the container, a flexible conduit having one end connected to the inlet pipe and the opposite end normally sustained by the support, a barrel in the container, a piston in the barrel, means for connecting the piston to the support, means for admitting fluid pressure to the barrel to elevate the support, and means for sustaining the support in elevated position in the container.

4. In apparatus of the character described, a container, an inlet pipe extending into the container, a movable support in the container, a flexible conduit having one end connected to the inlet pipe and the opposite end normally sustained by the support, a barrel in the container, means for movably supporting the barrel in vertical relation with the container, a piston in the barrel, means for connecting the piston to the support, means for admitting fluid pressure to the barrel to elevate the support and means for sustaining the support in elevated position in the container.

5. In apparatus of the character described, a container, a movable support in the container, a barrel in the container, a piston in the barrel, means for movably supporting the barrel in vertical relation with the con-

- tainer, a guide on the container for said means, a rod for connecting the support to the piston, and means for admitting fluid pressure to the barrel to elevate the piston.
- 5 6. In apparatus of the character described, a container, a movable support in the container, a barrel in the container, a piston in the barrel, means for movably supporting the barrel in vertical relation with the container including spaced rods on opposite sides of the container wall, a guide for one of said rods, means on the rods for manually elevating said barrel, means for connecting the support to the piston, means for admitting fluid pressure to the barrel to elevate the support, and means for sustaining the support in elevated position in the container.
- 10 7. In apparatus of the character described, a container, a movable support in the container, a barrel in the container, a piston adapted to reciprocate in the barrel, said barrel having a relief port at a point below the piston with the piston at its upward limit of travel, means for movably supporting the barrel in vertical relation with the container, a guide on the container for said means, a rod for connecting the support to the piston, and means for admitting fluid pressure to the barrel to elevate the piston.
- 15 8. In apparatus of the character described, a container, an inlet pipe extending into the container, a movable support in the container, a flexible conduit having one end connected to the inlet pipe and the opposite end normally sustained by the support, a barrel in the container, a piston adapted to reciprocate in the barrel, said barrel having a relief port at a point below the piston with the piston at its upward limit of travel, means for connecting the piston to the support, and means for admitting fluid pressure to the barrel to elevate the support.
